UNITED STATES PATENT OFFICE.

FREDERICK MANKEY, OF WILLIAMSPORT, PENNSYLVANIA.

DESIGN FOR A PANEL.

SPECIFICATION forming part of Design No. 17,063, dated February 1, 1887.

Application filed December 30, 1886. Serial No. 223,055. Term of patent 7 years.

To all whom it may concern:

Be it known that I, FREDERICK MANKEY, of Williamsport, Lycoming county, Pennsylvania, have invented and produced a new and original Design for Panels, of which the following is a specification.

Figure 1 represents my new design, and Fig. 2 a modification thereof.

Similar letters of reference indicate like parts.

My design consists in the four raised parallelograms A B C D and the square elevation E, with intermediate channels or intervals. The square elevation E has beveled or inclined sides and occupies the center of the design. The raised parallelograms A B C D have each a side parallel to a side of the elevation E, and are disposed relatively at right angles to one another. Between the elevation E and the parallelograms A B C D are channels F G H I. The channels F G H I appear respectively prolonged to extend between the parallelograms A B C D. A different grain-marking may appear upon the inclined edges J of the several elevations, which edges extend transversely the panel from that which appears upon the inclined edges K of said elevations, which edges extend laterally the panel.

Fig. 2 represents a modification of my aforementioned design, wherein, in place of showing bevelled edges upon the several edges of the elevations, I show stepped edges, more than two steps appearing upon each edge. The upper surface of the elevations is flat.

I claim—

1. The design for a panel, substantially as is herein shown and described, which consists in the raised parallelograms A B C D, the rectangular elevation E, and the intermediate channels, F G H I. 35

2. The design for a panel, substantially as herein shown and described, which consists in the raised parallelograms A B C D and the rectangular elevation E, said parallelograms and elevation having inclined sides or edges, 45 and the intermediate channels, F G H I, a different grain-marking appearing upon the inclined edges J from that which appears on inclined edges K. 40

3. The design for a panel, substantially as herein shown and described, which consists in the raised parallelograms A B C D, the rectangular elevations E, the sides or edges J K of said parallelograms and elevations appearing stepped with more than two steps, and the 55 intermediate channels, F G H I. 50

FREDERICK MANKEY.
